PATENT AGENCY

(57) **CLAIM**

The ornamental design of a switch button device, as shown and described.

DESCRIPTION

FIG. 1 is a perspective view of the switch button device;

FIG. 2 is a front view thereof;

FIG. 3 is a right side view thereof;

FIG. 4 is a left side view thereof;

FIG. 5 is a top end view thereof;

FIG. 6 is a bottom end view thereof; and,

FIG. 7 is a rear view thereof.

The broken lines in the drawings depict portions of the switch button device that form no part of the claimed design.
